UNITED STATES PATENT OFFICE.

HENRY C. FAIRCHILD, OF BRIDGEPORT, CONNECTICUT, ASSIGNOR TO THE FAIRCHILD & SHELTON COMPANY, OF BRIDGEPORT, CONNECTICUT, A CORPORATION OF CONNECTICUT.

SOAP-POWDER CANISTER.

No. 854,411.

Specification of Letters Patent.

Patented May 21, 1907.

Application filed May 31, 1906. Serial No. 319,649.

To all whom it may concern:

Be it known that I, HENRY C. FAIRCHILD, a citizen of the United States, residing at Bridgeport, in the county of Fairfield and State of Connecticut, have invented certain new and useful Improvements in Soap-Powder Canisters; and I do hereby declare the following to be a full, clear, and exact description of the invention, such as will enable others skilled in the art to which it appertains to make and use the same.

My invention relates to soap powder canisters and consists in certain novel combinations of parts and arrangements of parts, such as will be hereinafter fully described and then particularly pointed out in the claims which conclude this application.

In the accompanying drawing which forms a part of this application Figure 1 is a central vertical sectional elevation—Fig. 2 is a section similar to Fig. 1 but taken in a plane at right angles thereto—Fig. 3 a side elevation of my improved canister with the agitator lever sectioned away—Fig. 4 a view similar to Fig. 3 but showing a slightly modified form of my improvement, and Fig. 5 a bottom view.

Similar numbers of reference denote like parts in the several figures of the drawing. The object of my invention is to improve upon the construction shown and described in Letters Patent No. 464,315, issued December 1, 1891, to Frederick S. Fairchild. In this patented construction vertically disposed agitator rods extended up into the canister and were provided with laterally extending fingers, and when these rods were operated up and down the fingers would pass through the powdered soap so as to agitate the same and cause it to settle down toward the discharge opening. This construction

has been found to be very efficient so long as the soap powder remained in a thoroughly dry state, but when said powder became even slightly impregnated with moisture the vertically moving slide rods and agitator fingers would simply cut a path through the soap and the latter would merely become packed more densely without settling down toward the discharge opening.

The object of my present invention is to cure these defects by imparting to the agitator additional movements at right angles to the vertical movements.

1 is the canister, 2 and 3 upper and lower cross webs within the canister, 4 the main vertically disposed slide rod extending through said webs and guided thereby, 5 are agitator fingers extending laterally from said rod,

6 is a vertically disposed agitator rod having extending laterally therefrom fingers 7,

8 is a cross bar beneath the lower web 3 to which bar are secured the lower extremities of the rods 4 and 6, 9 an enlarged discharge opening in the lower web 3 and through which the rod 6 extends,

10 is a coil spring around the rod 4 and confined between the fingers 5 and the web 3, the function of this spring being to keep the rods 7 and cross bar normally in elevated position with the cross bar blocking the opening 9,

11 is a lever extending horizontally from the cross bar through the side of the canister, and 12 is any suitable eye block secured to 75 the side of the canister for attachment to any suitable bracket (not shown) whereby the canister may be secured in position convenient to a washbowl, all of these parts being constructed, arranged and operated precisely as is shown and described in the Letters Patent aforesaid.

In my present improvement I provide in the side of the canister a slot 13 whose side edges are curved, and the lever 11 extends 85 snugly through this slot so that when said lever is thrown down by the hand and returned by the action of the spring the rod 4 will be reciprocated vertically and at the same time rocked around its axis while the 90 rod 6 will be vibrated in addition to its vertical reciprocations, these movements of the rods causing the agitator fingers to have both vertical and lateral movements through the powdered soap.

In Fig. 3 I have shown a plain arcuate slot, but this may be varied by making the slot sinuous as shown at 14 in Fig. 4, in which latter instance the vertical movements of the lever 11 will effect an increased number of 100 vibrations of the agitator fingers.

When my present improvement is used the powdered soap will be agitated under all ordinary conditions and will be caused to flow freely toward the discharge opening 9 so that 105 when the lever 11 is forced downwardly the powdered soap will flow through said opening into the hand of the manipulator.

Having thus described my invention what I claim as new and desire to secure by Letters Patent is:—

1. In a soap canister, the combination of 5 the receptacle for containing the powdered soap having secured therein upper and lower cross webs the latter provided with an enlarged discharge opening, the vertically disposed main slide rod extending loosely 10 through said webs and guided thereby and provided with laterally extending agitator fingers, the coil spring around said rod and confined between said fingers and the lower web, the vertically disposed agitator rod ex- 15 tending through said discharge opening and provided with laterally extending agitator fingers, the cross bar immediately below said lower web and to which are secured the lower extremities of said rods and adapted to nor- 20 mally close said discharge opening, the curved slot formed within the side of said canister, and the operating lever extending from said cross bar snugly through said slot.
2. In a soap canister, the combination of 25 30 the receptacle proper having a discharge opening in its bottom and a downwardly leading curved slot in its side, suitable agitator rods extending up within the receptacle through the bottom thereof, the cross bar immediately below the bottom of the receptacle and to which the agitator rods are se-

cured, a spring element for normally elevating said rods and cross bar whereby the latter will close said discharge opening, and an operating lever extending laterally from said cross bar through the curved slot in the side of the receptacle whereby both vertical and horizontal reciprocations will be imparted to the agitator rods and the parts carried thereby.

3. In a soap canister, the combination of the receptacle proper having upper and lower cross webs and a discharge opening within the lower web and provided in its side with a vertically disposed slot whose side 45 edges are curved, agitator rods extending within the receptacle, a cross bar immediately below the lower web and to which said rods are secured, said cross bar adapted in its elevated position to close said discharge 50 opening, a spring element for keeping said cross bar and rods in a normally elevated position, and the operating lever extending from said cross bar laterally through said slot.

In testimony whereof I affix my signature in presence of two witnesses.

HENRY C. FAIRCHILD.
